UNITED STATES PATENT OFFICE.

RICHARD G. LEDIG, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

DESIGN FOR BASE FOR A STAND OF AN ELECTRIC HEATER.

56,009.

Specification for Design.

Patented Aug. 10, 1920.

Application filed December 22, 1919. Serial No. 346,800. Term of patent 7 years.

To all whom it may concern:

Be it known that I, RICHARD G. LEDIG, a citizen of the United States, residing in the city and county of Philadelphia, State of Pennsylvania, have invented a new, original, and ornamental Design for Bases for Stands of Electric Heaters, of which the following is a specification, reference being

had to the accompanying drawing, forming part thereof.

The figure is a perspective view of a base for a stand of an electric heater.

I claim:—

The ornamental design for the base for a stand of an electric heater, as shown.

RICHARD G. LEDIG.
